UNITED STATES PATENT OFFICE.

ARTHUR G. HATCH, OF DULUTH, MINNESOTA.

CONCRETE WALL CONSTRUCTION.

Application filed April 5, 1924. Serial No. 704,353.

To all whom it may concern:

Be it known that I, ARTHUR G. HATCH, a citizen of the United States, residing at Duluth, in the county of St. Louis and 5 State of Minnesota, have invented certain new and useful Improvements in Concrete Wall Constructions, of which the following is a specification.

This invention relates to a new and improved wall construction and more particularly to a construction involving adjacently placed walls with tying means connecting the two walls.

In certain types of walls, in order to have 15 increased stability and insulating effect with a minimum of concrete or other wall material, the walls are formed of two spaced walls which are tied together. This tying together is essential in order to preserve the 20 strength and stability of the wall.

With double walls of this character it is extremely difficult to maintain the joints between the blocks in the two walls directly opposite. Due to the slight variation in the 25 lengths of blocks and also due to slight variation in thickness of mortar joints between blocks there will not be exact registration. These errors may more or less compensate throughout the wall so that the 30 joints are substantially opposite, but in stretches of wall of considerable area cumulative error is likely to occur, such as to cause a marked lack of registration in some portions of the wall. This lateral displacement renders impractical the use of tie 35 blocks as generally constructed making closely fitting right angle joints with the wall blocks.

It is an object of the present invention 40 to provide a new and improved wall construction whereby adjacent walls may be tied together without exact registration of block joints.

It is a further object to provide a construction of this character using blocks of simple design and without special forms.

Other and further objects will appear as the description proceeds.

I have illustrated a preferred embodiment 50 of my invention in the accompanying drawings, in which—

Figure 1 is a plan view of the section of wall showing the joints on the opposite walls in registration; and

55 Figure 2 is a view similar to Figure 1

but showing the wall joints laterally displaced relative to each other.

The wall construction comprises a pair of spaced walls 11 and 12, the wall 11 being formed of a plurality of blocks 13 and the 60 wall 12 of a plurality of blocks 14. The blocks 13 and 14 may or may not be identical as desired. The blocks 13, as shown, are provided with the cavities 15 which permit a reduction of the amount of material used 65 to form the blocks. The blocks 11 are formed at their ends with the recess 16 which has an enlarged portion 17, reduced neck 18 and the flaring portion 19. The block 12 is provided at each end with ex- 70 acitly similar recesses.

The tie blocks 20 are provided with the enlarged heads 21 and, as shown, are provided with the metal reinforcements 22. The heads 21 of the blocks 20 are consider- 75 ably smaller than the recesses formed by the ends of adjacent blocks. As shown in the drawings, the thickness of the body portion of the block 20 is substantially equal to the distance between the portions 18 of 80 the recessed end faces of the blocks.

As shown in Figure 2, the configuration of the recess is such as to permit the tie blocks to be put in place although there is consider- 85 able displacement between the joints on the opposite walls. It will be understood that when the tie block is put in place the remainder of the recess will be filled with the mortar 23. It will be noted that both of the 90 faces of the wall are formed only of the main blocks, the tie blocks not extending to these faces.

I have illustrated one preferred form of construction but my invention is obviously adapted for use with blocks of differing configuration and I contemplate such changes and modifications as come within the scope of the appended claims.

I claim:

1. In a wall construction, a pair of oppo- 100 sitely placed walls formed of wall blocks, opposed recesses formed in the ends of juxtaposed blocks, tie blocks connecting the two walls, the tie blocks having enlarged ends fitted in the recesses formed between the adjacent blocks, the ends being smaller than the recesses whereby the tie blocks may be angularly disposed to connect walls having the block joints laterally displaced relative 105 to each other.

2. In a wall construction, a pair of oppositely placed walls formed of wall blocks, opposed recesses formed in the ends of juxtaposed blocks, the recesses having large inner portions and reduced portions communicating with the inner faces of the walls, tie blocks connecting the two walls, the tie blocks having enlarged ends fitted in the recesses formed between the adjacent blocks, the ends being smaller than the recesses whereby the tie blocks may be angularly disposed to connect walls having the block joints laterally displaced relative to each other.
- 5 3. In a wall construction, a pair of oppositely placed walls formed of wall blocks, opposed recesses formed in the ends of juxtaposed blocks, the recesses having large inner portions and reduced portions communicating with the inner faces of the walls, tie blocks connecting the two walls, the tie blocks having enlarged ends fitted in the recesses formed between the adjacent blocks, the ends being smaller than the recesses whereby the tie blocks may be angularly disposed to connect walls having the block joints laterally displaced relative to each other.
- 10 4. In a wall construction, a pair of oppositely placed walls formed of wall blocks, opposed recesses formed in the ends of juxtaposed blocks, the recesses having large inner portions and reduced portions communicating with the inner faces of the walls, tie blocks connecting the two walls, the tie blocks having enlarged ends fitted in the recesses formed between the adjacent blocks, the ends being smaller than the recesses whereby the tie blocks may be angularly disposed to connect walls having the block joints laterally displaced relative to each other.
- 15 5. In a wall construction, a pair of oppositely placed walls formed of wall blocks, opposed recesses formed in the ends of juxtaposed blocks, the recesses having large inner portions and reduced portions communicating with the inner faces of the walls, tie blocks connecting the two walls, the tie blocks having enlarged ends fitted in the recesses formed between the adjacent blocks, the ends being smaller than the recesses whereby the tie blocks may be angularly disposed to connect walls having the block joints laterally displaced relative to each other.
- 20 6. In a wall construction, a pair of oppositely placed walls formed of wall blocks, opposed recesses formed in the ends of juxtaposed blocks, the recesses having large inner portions and reduced portions communicating with the inner faces of the walls, tie blocks connecting the two walls, the tie blocks having enlarged ends fitted in the recesses formed between the adjacent blocks, the ends being smaller than the recesses whereby the tie blocks may be angularly disposed to connect walls having the block joints laterally displaced relative to each other.
- 25

Signed at Duluth, Minn., this 20th day of March, 1924.

ARTHUR G. HATCH.
